VALVE GUIDE AND UNSEATER

Norris F. McNaught and Edward H. Peterson,
Chicago, Ill., assignors to Duro Metal Products
Company, Chicago, Ill., a corporation of Illinois

Application November 9, 1931, Serial No. 573,817

5 Claims. (Cl. 51—262)

Our invention relates to a valve guide and unseater, particularly adapted for grinding the valves of internal combustion engines having removable valve stem guides.

- 5 In the well known Ford engine, as now constructed, the stems of the valves are provided with integral lower ends of greater diameter than are the portions of the stems which are embraced by the valve stem guides. In order 10 that the stems and guides may be assembled in operative relationship, the guides are formed in removable sections, necessarily removable with the valves, and held in position by the springs which urge the valves to their seats.
- 15 It has been found very difficult to grind the valves of engines having the aforesaid structural peculiarities. Firstly, the sectional valve guides of the engine are not available for use when the valve springs which hold the valve guide sections in position are removed. Secondly, there 20 has been a lack of satisfactory abutments for the unseating springs which are used during the valve grinding operation.

In the accompanying drawing illustrating a 25 preferred embodiment of our invention,

Fig. 1 is a side elevational view of the device of the present invention;

Fig. 2 is a side elevational view of the same illustrating the device in open position;

30 Fig. 3 is a horizontal sectional view taken on the line 3—3 of Fig. 1;

Fig. 4 is a vertical sectional view showing the device of the present invention as it appears ready for use in a valve grinding operation; and

35 Fig. 5 is a vertical sectional view of the block, valve, sectional valve stem guides, valve spring, etc. of an engine of the kind with which the device of our invention primarily is intended to be used.

40 Similar characters of reference refer to similar parts throughout the several views.

Referring first to Fig. 5, at 6 we have illustrated a portion of an engine block provided with a seat 7 with which a poppet valve cooperates. 45 The valve comprises a hub 8 and a stem 9, the stem having an enlarged integral lower extremity 10 which is frusto-conical in shape. At 11 we have shown the U-shaped washer which embraces and bears against the enlarged stem portion 10 and constitutes an abutment for the lower end of the valve spring 12. The valve stem guide consists of two complementary separable and removable sections 13 and 14 received within the guide bore 15 of the engine block. Each 55 guide section is provided with a semi-circular ex-

ternal shoulder 16 which bears against the adjacent portion of the block 6. The shoulders 16 together provide an annular shoulder which constitutes an abutment for the upper end of the 60 spring 12.

It has been extremely difficult to grind valves of the kind above mentioned because removal of the spring 12, which holds the separable and removable guide sections 13 and 14 in position, renders the latter unavailable for use in the valve 65 grinding operation.

The device of our present invention, shown in Figs. 1 to 4 inclusive, comprises a pair of complementary hinged metal members 17 and 18, each comprising a semi-cylindrical stem guide portion 19 merging at a shoulder 20 into a head portion 21. The head portions 21, 21 are hinged together by pivot pin rivets 22, 22, which extend through the cooperating hinge ears 22a, 22a which are formed on the said head portions 21, 21, as shown. Each of the head portions 21, 21 also is provided with a pair of stop lugs 23, 23 which are adapted to engage the corresponding lugs of the other head portion to prevent separation of the stem guide portions 19, 19 to a greater degree than is illustrated in Fig. 2.

The stem guide portions 19, 19 of the hinged members 17 and 18 are provided with machined complementary semi-cylindrical grooves 24, 24 adapted snugly to embrace the stem 9 of the engine valve as shown in Fig. 4. The head portions 21, 21 of the members 17 and 18 are provided with relatively large complementary and opposed recesses 25, 25 through which the enlarged lower extremity 10 of the valve may be passed downwardly when the members 17 and 18 are in their open positions as shown in Fig. 2.

The head portions 21, 21 of the hinged members 17 and 18 are provided with diametrically opposite apertured ears 26, 26, the apertures of the ears being so located that the line between them lies above the common axis of the pivots 22, 22 when the members 17 and 18 are separated as shown in Fig. 2; the line between said apertures falling below the said axis when the hinged members are closed together as shown in Fig. 1.

At 27 we have shown a coil spring, the lower convolutions of which embrace the head portions 21, 21 of the hinged members 17 and 18, the lowest convolution of the spring extending through the apertures of both of the lugs 26, 26 as shown, and being provided with an offset end 28. Head portion 21 of member 18 is provided with an outwardly extending pin 29 which limits movement of the spring extremity 28 to that 110

short distance between said pin 29 and the adjacent ear 26.

By reason of the arrangement shown, the pressure of the lowermost convolution of the spring 27 against the head portions 21, 21 of the hinged members 17 and 18 tends to hold the latter in their open positions when opened and in their closed positions when closed. This characteristic of the device of our invention facilitates its application to the valve and also facilitates its insertion into the engine valve stem bore 15. Further to facilitate the insertion of the stem guide portions 19, 19 into the engine stem guide bore, the lower ends of the said stem guide portions 19, 19 preferably are externally beveled, as indicated at 30, 30.

In using the device of our invention (the valve, valve spring and sectional valve stem guide being removed from the engine block) it is opened as shown in Fig. 2, and the enlarged lower extremity of the valve stem is passed downwardly through the spring 27 and the recesses 25, 25 of the head portions 21, 21. The device then is closed upon the valve stem and the stem guide sections 19, 19 are inserted into the stem guide bore 15 of the engine, as is shown in Fig. 4. In this situation, the spring 27 acts as an unseating spring tending to hold the valve slightly off of its seat. Grinding of the valve then proceeds in a well known manner.

Having thus illustrated and described a preferred embodiment of our invention, what we claim is new and desire to secure by Letters Patent of the United States is:

- 35 1. In a device of the class described, a pair of valve stem embracing members, said members comprising guide portions having opposed semi-cylindrical grooves and head portions having opposed grooves larger than those of the guide portions, means pivotally connecting said members on a transverse axis at their head portions and a coiled unseating spring carried by and projecting upwardly from the head portions of said members, the lowermost convolution of said spring embracing said head portions and being attached to the latter at points which lie below their pivotal axis when the unpivoted lower portions of said members lie in engagement with each other.
- 40 2. In a device of the class described, a pair of valve stem embracing members, said members comprising guide portions having opposed semi-cylindrical grooves and head portions having opposed grooves larger than those of the guide portions, means pivotally connecting said members on a transverse axis at their head portions and a coiled unseating spring carried by and projecting upwardly from the head portions of said members, the lowermost convolution of said spring embracing said head portions and being attached to the latter at points which are adapt-

ed to lie above their pivotal axis when the lower portions of said members are swung apart and which lie below said axis when said lower portions engage each other, whereby said spring tends to hold said members in the closed relationship when closed and in the open relationship when opened.

3. A device of the class described comprising a pair of substantially symmetrical valve stem guide members shaped for insertion into the valve stem guide bore of an engine and provided at their lower portions with opposed semi-cylindrical grooves adapted to embrace the cylindrical portion of a valve stem, said members being pivoted together at their upper ends and having the opposed surfaces of their upper portions conformed to pass a valve stem extremity of greater diameter than the passage defined by the opposed semi-cylindrical grooves of the said lower portions, together with an unseating spring carried by and extending upwardly from said members and so related to their pivotal axis as to hold them in the closed relationship when closed and in the open relationship when opened.

4. A device of the class described comprising a pair of substantially symmetrical valve stem guide members shaped for insertion into the valve stem guide bore of an engine and provided at their lower portions with opposed semi-cylindrical grooves adapted to embrace the cylindrical portion of a valve stem, said members being pivoted together on a transverse axis at their upper ends and having the opposed surfaces of their upper portions conformed to pass a valve stem extremity of greater diameter than the passage defined by the opposed semi-cylindrical grooves of the said lower portions, together with an unseating spring carried by and extending upwardly from said members and adapted yielding to hold them closed on each other when in that relationship.

5. A device of the class described comprising a pair of substantially symmetrical valve stem guide members shaped for insertion into the valve stem guide bore of an engine and provided at their lower portions with opposed semi-cylindrical grooves adapted to embrace the cylindrical portion of a valve stem, said members being pivoted together on a transverse axis at their upper ends and having the opposed surfaces of their upper portions conformed to pass a valve stem extremity of greater diameter than the passage defined by the opposed semi-cylindrical grooves of the said lower portions, together with an unseating spring carried by and extending upwardly from said members and so related to their pivotal axis as to hold them in the closed relationship when closed and in the open relationship when opened.
